UNITED STATES PATENT OFFICE.

PHILO M. CLARK, OF KANSAS CITY, MISSOURI.

IMPROVEMENT IN PORTABLE OIL-TANKS.

Specification forming part of Letters Patent No. 172,609, dated January 25, 1876; application filed January 4, 1876.

To all whom it may concern:

Be it known that I, PHILO M. CLARK, of Kansas city, in the county of Jackson and State of Missouri, have invented certain new and useful Improvements in Oil-Wagons; and I do hereby declare the following to be a full, clear, and exact description thereof, reference being had to the accompanying drawing and to the letters of reference marked thereon.

The object of my invention is to safely carry, correctly measure, and speedily transfer without waste, loss, or danger, kerosene and other carbon oils, to smaller receptacles within stores, warehouses, vessels, or other places; and to this end the nature of my invention consists in the construction and arrangement of an oil-tank, with attachments mounted upon a wagon, as will be hereinafter more fully set forth.

In order to enable others skilled in the art to which my invention appertains to make and use the same, I will now proceed to describe its construction and operation, referring to the annexed drawing, in which—

Figure 1 is a plan view, and Fig. 2 a side elevation, of my invention.

A represents a wagon-truck or frame mounted upon wheels B, and provided with a tongue, C, for the attachment of the team. D represents a cylindrical tank, made of wood or metal, and hung upon trunnions *a a* in boxes *b b* on the wagon-frame. The rear end of the tank D is supported upon an adjusting-screw, E, passing upward through a cross-bar in the rear end of the frame. This screw E is used to level the tank, for which purpose a spirit-level, *d*, is attached to the side of the tank near the center. In the rear end or head of the tank is inserted a graduated glass tube, *h*, running from top to bottom, and showing the precise amount of oil in the tank.

The oil is admitted into the tank through an opening, *e*, in the top. From near the bottom of the tank, in the rear end, passes a tube, *f*,

provided with a stop-cock, *i*, used for regulating the flow of oil from the tank when delivering, and to confine the oil within the tank at other times. The pipe *f* leads into a rotary pump, G, supported upon a platform, H, attached to the tank. This pump is used, when necessary, to force the oil from the tank through the hose or pipe into other receptacles which may be on higher levels than itself, or when, for any reason, the oil will not reach them by gravitation. The hose or pipe I conveys the oil from the tank to the receiving-vessels either by the use of the pump or by gravitation, and in said pipe is a stop-cock, *m*, to prevent wastage. When the oil is passed from the tank by means of gravitation alone the hose or pipe may be connected directly with the pipe *f*. On the top of the tank is a safety-cock, *n*, to permit of the escape of gases which may accumulate.

By this device kerosene and other carbon oils may be carried safely, correctly measured, and speedily transferred to other receptacles, without waste, loss, or danger.

Having thus fully described my invention, what I claim as new, and desire to secure by Letters Patent, is—

1. An oil-tank, suspended upon trunnions on a wagon-frame, and leveled by means of an adjusting-screw, for the purposes herein set forth.

2. The pivoted tank D, provided with the spirit-level *d* and glass gage *h*, in combination with the wagon A B and adjusting-screw E, substantially as and for the purposes herein set forth.

3. The combination of the tank D, pipe *f*, with stop-cock *i*, pump G, and pipe I, with stop-cock *m*, substantially as and for the purposes herein set forth.

PHILO M. CLARK.
